UNITED STATES PATENT OFFICE

IRVING E. ASKE, OF MINNEAPOLIS, MINNESOTA

VAPORIZER

Application filed January 24, 1930. Serial No. 423,130.

My invention relates to vaporizers and has for its object the improvement of electric vaporizers for converting hydrocarbon fuel into hot fumes for use in starting a cold internal engine, and for such other or further uses as it may be adapted to serve. It consists of the structures, combinations, and arrangements of parts hereinafter described and claimed.

10 In the drawings, Fig. 1, is an enlarged central vertical section of a vaporizer embodying my said invention omitting the hereinafter described screen. Fig. 2 is a horizontal section of the same approximately 15 on the line A—B of Fig. 1. Fig. 3, is a vertical section of the same invention approximately on the line C—D of Fig. 2 omitting the hereinafter described pads and showing said screen.

20 My present invention is designed to be an improvement upon the structure disclosed in my Patent Number 1,758,020, in which prior structure are embodied a plurality of absorbent pads, some of which, corresponding substantially to the hereinafter described pads 8, 9, 10 and 11, are in said prior structure positioned in contact with certain resistance members corresponding to the hereinafter described resistance members 4 25 and 5, in which positions, although serviceable, the contacting pads tend, under prolonged use at very high temperature, to char, and to clog the fuel conducting wells and vapor exhaust passages with charred 30 material. To avoid these imperfections in said prior structure is one purpose of my present invention; but I do not mean that my present invention is restricted to the improvement of the specific structure disclosed 35 in said prior structure since my present invention may be adapted to use with and may extend to other forms of vaporizers.

In the drawings, 1 is a vaporizer cup of any suitable form or construction adapted to 40 be cast upon or by any suitable means, as

by ears 1^a, secured to the air intake horn, or intake manifold of an internal explosion engine, or other fuel conductor (not shown) which it may serve, and to discharge thereinto. Said cup is closed at the bottom by 50 a plug 2, through which extends a binding post 3 electrically insulated from said plug in any suitable manner, or by any suitable means, as by intervening washers 3^a, of insulating material. Electrically connected at 55 one end to the head of said post within a recess 2^a in said plug, are resistance members 4 and 5 which at their opposite ends are grounded on said cup in any suitable manner and by any suitable means.

Extending into the recess in said plug is 60 a cylindrical heat insulating sheath 6 of any suitable heat insulating material as mica, and a concentric cylindrical protective shell 7, preferably of metal.

At each side of each of the resistance members is a very thin absorbent member or pad as 8, 9, 10, 11, respectively, each preferably about one thirty second of an inch thick and extending across the bore of said cylindrical heat insulating sheath 6, which surrounds, and is preferably spaced from 70 said resistance members.

Between the central pair of said thin pads which may also be referred to as the central intermediate pads, are a pair of comparatively thick absorbent central pads, 12 and 13, positioned oppositely to and parallel with each other in a plane parallel to the side faces of said central intermediate pads and spaced from each other preferably about one-eighth of an inch more or less, to form a well 14, in which fuel oil may rise or fall freely. Said central pads extend in opposite directions from said well to the walls of 75 said heat insulating cylinder. Each of said central and central intermediate pads extends from the top of the head of said binding post approximately to the upper ends 80 of said resistance members.

The outward pair of said thin pads may be called the outer intermediate pads and they preferably extend from the top of the head of said post approximately to the upper ends of said resistance members.

5 Against the outward side face of each of the outward intermediate pads, I position a relatively thick pad, as 15 and 16, respectively, which may be referred to as the outward pads. Said outward pads preferably extend from the bottom of said recess in said plug, approximately to the upper ends of said resistance members, and extend transversely from the respectively adjoining outer intermediate pads to the wall of said sheath, and extend parallel with said outer intermediate pads, from the wall in one quadrant of said sheath to the wall of an adjoining quadrant thereof.

10 Advantage is preferably taken, however, of the curve of said sheath to provide vertical spaces or wells, as in 17 and 18, between said sheath and the central parts of the relatively flat outer faces of each of said outer pads, respectively, wherein fuel oil may flow, and to form other oil spaces or corner wells, as 19, 20, 21 and 22 between the inward edges of said outward pads and the respectively adjoining walls of said sheath and the respectively adjoining outer intermediate pads.

15 Each of said outward pads also has formed in its inward face a vertical groove co-operating with the side of the respectively adjoining outer intermediate pad to form intermediate wells, 23 and 24, respectively, in which fuel oil may freely rise or fall.

20 Said sheath has any suitable number and form of intake ports, as 25, formed therein near its lower end adapted to register with corresponding intake ports 26 in said shell. Said intake ports in said sheath are preferably in the form of wide and highly slotted apertures, thereby permitting the 25 registration with the ports in said shell to be more easily and cheaply effected during assembly.

25 Said sheath extends from a horizontal plane a short distance within the recess in said plug, to a horizontal plane slightly above the upper bends of said resistance members, and said shell extends approximately from the horizontal plane of the bottom of said sheath to a place a short distance above the upper end of said sheath.

30 Between the upper end of said sheath and the upper end of said shell is positioned a horizontal screen 27 preferably of porcelain, which is held in position by an inwardly directed annular flange formed on the upper end of said shell. Said shell is spaced from said cup and said cup has a fuel intake port formed therein at any suitable point as at 1^b adapted to communicate with 35 any suitable external source of supply and

with the space between said cup and said shell. The fuel oil will then enter said cup and flow through said shell and insulating cylinder ports, positioned preferably opposite the wells 17 and 18, and thence into the recess in said plug and may rise in the outer wells and flow over the top of the pads and down into one or more of the several other wells, at the same time soaking through the pads by capillary attraction or under hydrostatic pressure or both, and may flow across the head of said post, through a slot 3^b therein, from the intermediate to the central well. During the heating period liquid fuel may percolate in said wells and more promptly and effectively supply oil to all the levels of said pads than could be done by capillary attraction from the bottom alone through the thick pads.

35 Interposed between each of said intermediate pads and the respectively nearest of said resistance members, is a thin leaf or film of mica as 28, 29, 30 and 31, respectively, adapted to contact at one side with the intermediate pad and at the other side with the resistance member and to prevent contact between the intermediate absorbent pad and the resistance members and thus prevent scorching or charring of the absorbent pad. Said mica leaves serve to distribute the heat more evenly to the intermediate pads and are thin enough to permit sufficient heat to reach the intermediate pads to vaporize the hydrocarbon fuel distributed in them. Further, said mica leaves operate to form guides to the top of the vaporizer along which the vapor may flow to the exhaust ports in a manner similar to the manner in which such vapor formerly followed the wire of said resistance members to their upper bends.

40 If desired transverse apertures communicating with the outer, intermediate and central wells may be formed in said pads. But such structure would tend to make the assembling operation more difficult and expensive. The pads are held firmly together by the insulating sheath which is pressed over them and fits closely, and they are made of any suitable porous and incombustible material, preferably asbestos.

45 What I claim is—

1. The combination of a cup open at one end and closed at the opposite end and provided with an intake port, an electricity conducting post extending into said cup through its closed end and insulated therefrom, a pair of non-absorbent refractory leaves extending into said cup, an electric resistance member electrically connected at one end to the inward said post and grounded at its opposite end and extending intermediate of its ends between said leaves and in contact with the inward faces thereof,

absorbent members in contact with the outward faces of said non-absorbent leaves, a sheath of heat insulating material encircling said absorbent members leaves and resistance member and provided with a fuel intake port, a shell encircling said sheath and spaced for a part of its length from the side wall of said cup, and provided with an intake port adapted to communicate with the intake port of said sheath and with the space between said shell and the side wall of said cup.

2. The combination of a cup, a pair of non-absorbent refractory leaves extending into said cup, an electric resistance member extending into said cup between said leaves and in contact with the inward faces of said leaves, a sheath of heat insulating material encircling said leaves and resistance member and provided with an intake port, absorbent members positioned between the sides of said leaves and sheath, and a shell encircling said sheath and spaced for a part of its length from the side wall of said cup and provided with an intake port adapted to communicate with said space and with the intake port in said sheath.

3. The combination of a cup, two pairs of non-absorbent refractory leaves extending into said cup, electric resistance members extending between the leaves of each of said pairs, respectively, said pairs being spaced from each other, absorbent material positioned in the space between said pairs, a heat insulating sheath encircling said pairs and resistance members and provided with an intake port, absorbent material interposed between the outer sides of said pairs and said sheath, said absorbent material between said pairs and outwardly thereof having wells formed therein, other wells being formed between the side wall of said sheath and portions of said absorbent material, and a shell encircling said sheath and spaced for a part of its length from the side wall of said cup, said shell having an intake port formed therein adapted to communicate with the intake port in sheath and with the space between said shell and side wall of said cup, said vaporizer being adapted to discharge heated vapor from the upper level of the area encircled by said sheath.

4. In a vaporizer, the combination of a cup, an electric resistance member extending into said cup, leaves of non-absorbent non-conducting refractory material at opposite sides of said member, and absorbent material positioned at the opposite sides of said leaves from said resistance member said absorbent material being in contact with said leaves.

5. In a vaporizer, the combination of a cup provided with an intake port, an electric resistance member extending into said

cup, leaves of non-absorbent refractory material positioned at the opposite sides of said member, absorbent material positioned at the opposite sides of said leaves from said resistance member, and means for retaining said absorbent material in position and for retarding the radiation of heat therefrom, said means being provided with an intake port and an exhaust port.

In testimony whereof, I hereunto affix my signature.

IRVING E. ASKE.
